UNITED STATES PATENT OFFICE

158,935

SET OF GAME WEIGHTS

Ernest Correale, Jersey City, N. J.

Application June 29, 1948, Serial No. 147,279

Term of patent 3½ years

(Cl. D34—5)

To all whom it may concern:

Be it known that I, Ernest Correale, a citizen of the United States, residing at Jersey City, in the county of Hudson and State of New Jersey, have invented a new, original, and ornamental Design for a Set of Game Weights, of which the following is a specification, reference being had to the accompanying drawing, forming part thereof.

Fig. 1 is a top plan view of the set of game weights, showing my new design.

Fig. 2 is an enlarged edge view of weight #1 in Fig. 1.

Fig. 3 is an enlarged sectional view of weight #1 taken on line 3—3 in Fig. 1.

Fig. 4 is an enlarged edge view of weight #9 in Fig. 1.

Fig. 5 is an enlarged sectional view of weight #9 taken on line 5—5 of Fig. 1.

Fig. 6 is an enlarged edge view of the jack weight #J in Fig. 1.

Fig. 7 is an enlarged sectional view of the jack weight #J taken on line 7—7 in Fig. 1.

Fig. 8 is an enlarged edge view of the ballini weight, shown at the bottom of Fig. 1.

Fig. 9 is an enlarged sectional view of the ballini weight taken on line 9—9 in Fig. 1.

Weights #2 to #8 inclusive in Fig. 1 have substantially the same appearance as weight #1.

Weights #10 to #15 inclusive in Fig. 1 and the

unnumbered "cue-ball" weight in line 4 from the top of Fig. 1 have substantially the same appearance as weight #9.

Weights #Q, K and A in Fig. 1 have substantially the same appearance as weight #J.

The bottoms of all of the weights in the set of game weights are plain and unornamented.

The total number of weights in the set of game weights is 21.

The figures are hatched to show color contrast.

I claim:

The ornamental design for a set of game weights, as shown and described.

ERNEST CORREALE.
